UNITED STATES PATENT OFFICE.

DAVID O. KIMMEL AND JOHN KECK, OF DAYTON, OHIO.

BARREL-HOIST.

SPECIFICATION forming part of Letters Patent No. 469,703, dated March 1, 1892.

Application filed October 26, 1891. Serial No. 409,761. (No model.)

To all whom it may concern:

Be it known that we, DAVID O. KIMMEL and JOHN KECK, citizens of the United States, residing at Dayton, in the county of Montgomery and State of Ohio, have invented certain new and useful Improvements in Barrel-Hoists; and we do hereby declare that the following is a full, clear, and exact description of the invention, which will enable others skilled in the art to which it appertains to make and use the same, reference being had to the accompanying drawings, and to the letters of reference marked thereon, which form a part of this specification.

15 Our invention relates to improvements in barrel-hoists, the features of which will be fully hereinafter described and claimed.

The object of our invention is to hoist barrels with a view to placing the same in position to draw off the contents in retail establishments. The object is accomplished by the device shown in the accompanying illustration, in which—

Figure 1 is a side elevation of the device 25 with a portion cut away. Fig. 2 is a top view of the elevating-frame.

Like letters in the two views designate like parts.

The supporting-frame A comprises two uprights connected at the top by the cross-piece J, braced by two semicircular bars, one of which is movable, and the transverse cross-pieces K at bottom to form a base, which are made rigid by oblique braces. The rear 35 semicircular brace, corresponding to the brace F, is rigidly attached to the frame. The front brace is hinged to the right upright by the staple v and is secured to the left upright by a slot of said brace embracing the staple w, 40 through which a pin is passed to make the same fast.

In the top of the supporting-frame is secured the nut m, threaded to receive the screw C. In the enlarged top end of this screw in 45 a suitable orifice is held the handle D for operating said screw. The lower end of the screw is passed through an orifice in the elevating-frame B, the washer n, and is secured in position by the pin o. The elevating-frame 50 comprises four arms, the pairs arranged at a right angle. The longitudinal arms bear on the chine of the barrel and the transverse arms

may bear either on the chine or on the barrel-head. The sustaining-rods s are curved at their lower ends to engage the chine of a 55 barrel, and the threaded upperends enter orifices of said elevating-frame, and are secured therein by nuts bearing on the upper surface.

In the illustration the barrel G (shown in cross-section) is suspended in the frame or 60 hoist, and in this position the stool I (shown in dotted lines) is placed beneath for the permanent support of the barrel.

In Fig. 2 is shown a top view of the elevating-frame, and the circular line G' shows the 65 position of the barrel-chine.

The operation is thus described: Place the hoist over the up-ended barrel, put the sustaining-rods beneath the chines, then turn the nuts at the top until the elevating-frame is 70 firmly held against the top chine, fasten the semicircular brace, and turn the screw until the barrel is elevated to a proper height. To release the barrel, reverse the operation. The transverse arms of the elevating-frame can be 75 dispensed with.

Having fully described our invention, what we claim, and desire to secure by Letters Patent, is—

1. In a barrel-hoist, the combination of the 80 supporting-frame A, the elevating-frame B, provided with arms to engage the chine of a barrel, the supporting-rods s s, with hooks to engage the lower chine of a barrel, and the elevating-screw C, provided with a handle 85 and held in a nut in the top of said supporting-frame, substantially as set forth.

2. In a barrel-hoist, the combination of the supporting-frame A, provided with the rigid semicircular brace and a like movable brace, 90 the elevating-frame B, provided with arms, the supporting-rods s s, held in said arms and provided with hooks on their lower ends, and the screw C, held in the top of said supporting-frame, substantially as set forth. 95

In testimony that we claim the foregoing as our own we affix our signatures in presence of two witnesses.

DAVID O. KIMMEL.
JOHN KECK.
